UNITED STATES PATENT OFFICE.

WILLIAM A. RATCLIFFE, OF CHICAGO, ILLINOIS.

DESIGN FOR A WATER-CLOSET BOWL.

43,746.

Specification for Design.

Patented Mar. 25, 1913.

Application filed February 17, 1911. Serial No. 609,270. Term of patent 14 years.

To all whom it may concern:

Be it known that I, WILLIAM A. RATCLIFFE, a citizen of the United States, residing at Chicago, county of Cook, State of Illinois, have invented a new, original, and ornamental Design for Water-Closet Bowls, of which the following is a specification, reference being had to the accompanying drawing, forming part thereof.

In the drawing Figure 1 is a perspective view of the water closet bowl. Fig. 2 is a top plan view of the same, and Fig. 3 is a side elevation.

The structure shown comprises a bowl 1, of oval outline, which is supported on a base 2, said bowl carrying at its upper edge a protruding rim 3. At the back of the

bowl is a curved extension 4, having flat side-walls across one of which extends an enlargement or protrusion. The lower part 5, of this protrusion extends downward along the side of the structure and merges therein. The intermediate portion 6, is shaped into a tubular opening, and the upper part 7 merges in the side-wall somewhat below the edge of a flat platform 8, which forms a rear extension of rim 3.

I claim:—

The ornamental design for a water closet bowl as shown and described.

WILLIAM A. RATCLIFFE.
